[57] **CLAIM**

The design for a handled lunchbox, as shown and described.

DESCRIPTION

FIG. 1 is a top, front perspective view of a handled lunchbox showing our new design;

FIG. 2 is an exploded perspective view thereof;

FIG. 3 is a top plan view thereof;

FIG. 4 is a front elevational view thereof;

FIG. 5 is a bottom plan view thereof;

FIG. 6 is a rear elevational view thereof;

FIG. 7 is a side elevational view thereof of the opposite side of FIG. 6;

FIG. 8 is a side elevational view of the handled lunchbox from the opposite side thereof;

FIG. 9 is a transverse cross-sectional view thereof taken along the plane of the line 9—9 FIG. 3; and,

FIG. 10 is a longitudinal cross-sectional view thereof taken along the plane of the line 10—10 of FIG. 3.

FIG. 1

FIG. 2

FIG. 5

FIG. 6

FIG. 7

FIG. 8

FIG. 9

FIG. 10
